UNITED STATES PATENT OFFICE.

RAPHAEL ANGELO PILLA, OF PHILADELPHIA, PENNSYLVANIA.

DRAWER STOP.

Application filed July 13, 1926. Serial No. 122,103.

My invention relates to drawer stops and more particularly to stops adapted to prevent the accidental removal of a drawer from a cabinet. Drawers of type cabinets are often accidentally pulled out too far; thus dumping the contents on the floor and pieing the type, which causes a great deal of work in resorting.

The principal object of my invention is to produce a device that will eliminate this danger regardless of how carelessly the drawers are handled.

A further object of the invention is to produce this device of simple and strong construction which will be easily installed.

These objects, and other advantageous ends which will be described hereinafter, I attain in the following manner, reference being had to the accompanying drawings in which—

Figure 1 is a fragmentary plan view of a type cabinet section, shown partly in cross section, on which my invention has been installed,

Figure 2 is a side view, of the drawer shown in Figure 1, drawn to a larger scale,

Figure 3 is a fragmentary front view of the cabinet shown in Figure 1, certain parts being broken away,

Figure 4 is a cross sectional view of my device taken on line 4—4 of Figure 3, and

Figure 5 is a front view of the device shown in Figure 4.

Referring to the drawings, 6 represents a section of a type cabinet, 7 the top plate of same, 8 a drawer in which type is stored. The side rails of the drawer 8 contain grooves 9 which are deeper at the front of the drawer, as shown at 10, sloping outwardly for a short distance as shown at 11 and then tapering rearwardly to the full depth at the rear of the drawer, as illustrated at 12. 13 represents my device in its entirety which is installed in a recess 14 of the partition 15 of the cabinet 6 with the front of the device flush with the inner surface of the partition. The device consists of a metallic casing 16 having a cylindrical recess 17 in the approximate center of the casing 16, terminating against the rear wall of the casing in which a small aperture 18 is provided. Inserted in the recess 17 is a lock bolt 19 having a reduced rear portion 20, the end of which is threaded for reception of a nut 21. A coiled spring 22 encircles the reduced portion of the lock

bolt 19, the ends of the spring abutting the inner wall of the casing and the shoulder 23 formed by the junction of the reduced portion and the body of the lock bolt. Near the center of the lock bolt 19, a depression 24 is formed, the purpose of which will be later explained.

The upper wall of the casing 16 is provided with a small aperture 25 and the walls of the recess 17 are provided with larger apertures 26; the apertures 25 and 26 being in alignment. A catch 27, having a shoulder 28 formed by a reduced top portion 29, is inserted in the aperture 25 and the upper aperture 26. A coiled spring 30 encircles the reduced portion 29, the ends of which abut respectively against the inner side of the upper wall of the casing and the outer wall of the central aperture. The device is secured to the partition 15 by screws or the like being inserted through holes 31 of the front plate 32. The device is assembled in the following manner:

The catch 27 is passed upwardly through the two apertures 26 and the spring 30 placed on the reduced portion of the catch which is then raised still further until the reduced portion extends through the aperture 25 above the upper wall of the casing and is then riveted over or otherwise secured against return. The spring 22 is placed on the reduced portion 20 of the lock bolt 19 which is then inserted in the recess 17 and the reduced portion passed through the aperture 18. The nut 21 is then threaded onto the reduced portion and the entire device fastened into the recess 14 by means of screws or the like passing through the holes 31 and engaging the partition. The sides of the drawers of the cabinet are grooved as shown in Figures 1 and 2; the front of the drawer being grooved deep enough to admit the end of the lock bolt and then slope outwardly for a short distance so that the lock bolt rides in the bottom of the groove. The rear end of the groove sloping gradually to its full depth near the rear of the drawer at which point the lock bolt 19 is permitted to extend to its normal position, thus locking the drawer against accidental removal.

In case it is desired to remove the drawer, the lock bolts 19 are depressed by placing a thumb against the end of the bolt and turned until the catch 27 engages the grooved recess 24 which will retain the lock bolt in its withdrawn position. In Figure 3, the device

is shown with the lock bolt both extended and withdrawn. Adjustment of the lock bolt is made by means of the nut 21.

While I have described my invention as being applied to type cabinets and consisting of a particular form, it will be understood that it may be readily adapted to other purposes and that the various parts may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A drawer stop including a casing; a lock bolt slidably positioned in said casing; means for normally holding said bolt in an extended position; a catch positioned in said casing and adapted to normally abut against said bolt, said bolt being adapted to engage said catch.
2. A drawer stop including a casing having a cylindrical recess; a round-nosed lock bolt, adapted to engage a groove in a drawer side rail, in said recess; a compression spring, engaging the inner wall of the cas-

ing and shoulders formed on said lock bolt, to hold said lock bolt normally in an extended position; and means extending through said casing and into said recess to engage said bolt in a different position.

3. A drawer stop including a casing having a cylindrical recess; a round-nosed lock bolt, adapted to engage a groove in a drawer side rail, in said recess; a compression spring, engaging the inner wall of the casing and shoulders formed on said lock bolt, to hold said lock bolt normally in an extended position; and spring controlled means in said casing adapted to engage said lock bolt in a withdrawn position.

4. A drawer stop including a casing having a cylindrical recess, a lock bolt in said recess adapted to engage a groove in a drawer side rail, a compression spring engaging the inner wall of said casing to hold said lock bolt normally extended, a second spring and a pin controlled thereby for engaging said bolt in a withdrawn position, said bolt having a recess therein for engaging the pin.

In testimony whereof I have signed my name to this specification.

RAPHAEL ANGELO PILLA.
